United States Patent

Des. 235,189
Patented May 27, 1975

235,189

KEY

Ichiro Tachi, Fujisawa, Japan, assignor to Kabushiki
Kaisha Asakusa Gangu, Tokyo, Japan

Continuation of design application Ser. No. 24,709, Aug.
26, 1970, now Patent No. 222,999. This application
Aug. 3, 1971, Ser. No. 168,793

Term of patent 14 years

Int. Cl. D8—07

U.S. Cl. D8—136

FIG. 1 is a perspective view of the key embodying the present design and having a Z-shaped tip end;

FIG. 2 is a perspective view of a modification of the present key having a V-shaped tip end;

FIG. 3 is a perspective view of a modification of the present key having a T-shaped tip end;

FIG. 4 is a perspective view of a modification of the present key having an L-shaped tip end;

FIG. 5 is a perspective view of a modification of the present key having an I-shaped tip end;

FIG. 6 is a perspective view of a modification of the present key having a U-shaped tip end; and

FIG. 7 is a perspective view of a modification of the present key having an H-shaped tip end.

It is noted that in cross-section the shank of the key consists of four perpendicularly disposed legs. The side of the shank of the key not shown is therefore identical to that shown.

I claim:

The ornamental design for a key, as shown and described.
